FIG. 1

FIG. 2

FIG. 4

FIG. 3

FIGURE 1 is a front elevational view of a combined wall panel and foldaway table in folded position showing our new design;

FIGURE 2 is a perspective view thereof as it appears with the table in lowered position, the broken line showing of portions of the walls and floor being for illustrative purposes only;

FIGURE 3 is a side elevational view of the combined wall panel and foldaway table as seen in FIGURE 2; and

FIGURE 4 is a front elevational view thereof.

We claim:

The ornamental design for a combined wall panel and foldaway table, as shown and described.
